UNITED STATES PATENT OFFICE.

EDMUND TOKARSKI, OF PITTSBURGH, PENNSYLVANIA.

FIRE-ALARM BOX.

1,176,499.

Specification of Letters Patent. Patented Mar. 21, 1916.

Application filed August 27, 1915. Serial No. 47,646.

To all whom it may concern:

Be it known that I, EDMUND TOKARSKI, subject of the Emperor of Austria-Hungary, residing at Pittsburgh, in the county 5 of Allegheny and State of Pennsylvania, have invented certain new and useful Improvements in Fire-Alarm Boxes, of which the following is a specification.

This invention relates to certain new and 10 useful improvements in fire alarm boxes.

The primary object of this invention is the provision of an alarm box employed in connection with the fire alarm system which is used in cities, and whereby the hand of the 15 person sending in the alarm is locked to the box until released by some authorized person connected with the fire department.

A further object of the device is to provide an automatic arm-grasping means in 20 connection with a fire alarm box and whereby a person sending in an alarm is made a prisoner so that upon the arrival of the fire department the existence or location of the fire may be accurately ascertained.

25 A still further object is to provide a mechanism for preventing the turning in of false fire alarms in a city alarm system by reason of the fact that the operator of the alarm is held a prisoner at the alarm box until his 30 release by an officer upon the arrival of the fire department.

With these general objects in view and others that will appear as the nature of the invention is better understood, the same consists in the novel combination and arrangement of parts hereinafter more fully described, illustrated in the accompanying drawings, and pointed out in the appended claims.

40 In the drawings forming a part of this application and in which like-designating characters refer to corresponding parts throughout the several views, Figure 1 is a top plan view of the device partially broken away. Fig. 2 is a longitudinal sectional view thereof taken upon line II-II of Fig. 1. Fig. 3 is a horizontal sectional view taken upon line III-III of Fig. 2 with the mechanism in its normal released position.

45 Fig. 4 is a front elevation of the device partially broken away. Fig. 5 is a view similar to Fig. 3, but with the mechanism in its sprung arm-engaging position with the electric switch closed. Fig. 6 is a perspective 55 view of one of the arm-engaging members. Fig. 7 is a perspective view of the locking

slide employed with the arm-engaging member. Fig. 8 is a sectional view through the arm-engaging member with the operating finger broken away and with the slide illustrated by dotted lines in its locking position. Fig. 9 is a perspective view of the reset mechanism detached, and Fig. 10 is a similar view of the electric switch of the alarm box.

Referring more in detail to the drawings, 60 a fire alarm box 10 is illustrated of substantially the usual size and having a swinging forward door 11 adapted to be readily opened by any person desiring to send in an alarm. The electric switch of the fire 65 alarm system is positioned within the said box upon a bracket 12 and consists of an angular switch arm 13 pivoted to the said bracket as at 14 and having a contact 15 adapted to make electric connection with an 70 opposite contact 16 mounted upon the said bracket 12, while the circuit wires 17 and 18 of the alarm system are connected 75 respectively to the said terminals 15 and 16.

Arm engaging members 19 of the form 80 best illustrated in Fig. 6 and being right-angled in cross-section are vertically pivoted at opposite points inwardly of the box door 11 by means of trunnion pins 20 extending partially through the top and bottom of the box 10. The said arm engaging members 19 are provided with plates 21 adapted to overlap as best illustrated in Fig. 3 of the drawings when the device is 85 in its operative position and at which times the arm-engaging plates 22 will be outwardly extended in parallel relations, thus allowing the hand of the operator to be inserted upon opening the door 11 so as to push against the plates 21 and tilt the 90 members 19 upon their pivots until the plates 22 are in a single plane and the wrist of the operator is positioned through a central opening in the said plates formed by the U-shaped cut-away portions 23 thereof. 95

Wrist-locking plates 24 are slidably mounted within the chambers 25 of the plates 22 and are normally retained retracted by means of springs 26 carried by the plates 24 and secured to the inner faces 100 of the plates 21 by means of pins 27 extending through slots 28 in the said springs 26. The plates 21 are each provided with a perforation 29 adapted for the reception of a finger 30 of the adjacent one of opposite 110 angular arms 31 which are pivoted upon brackets 32 carried by the outer side of

opposite parallel partitions 33 of the box 10, the said fingers 30 freely extending through perforations 34 in the said partitions. The said arms 31 are connected by 5 springs 35 with the adjacent sides of the partitions 33, which springs normally hold the fingers 30 resiliently against the adjacent faces of the plates 22 at substantially the plane of the trunnion pins 20 when the 10 arm engaging members 19 are in their normal unlocking positions as shown in Fig. 3. The said arms 31 are provided with rear extensions 36 and 37 which have a pin and slot connection 38. The said arm end 37 is provided with an angular extension 39 terminating in a head 40 adapted to be received within the central longitudinal slot 41 of an angular end 42 of the switching arm 13 when the electric switch is open and the said 15 end 42 is slidably received and retained within the slots 43 of an angular plate 44 carried by the bracket 12, the elements being arranged as illustrated in Fig. 3.

The opposite ends of the trunnion pins 20 20 which project outwardly of the sides of the box 10 have segmental racks 45 in constant mesh with each other and inclosed within housings 46 carried by the sides of the box. The operator of the alarm pushes the plates 21 inwardly which operation shifts the member 21 to bring the openings 29 into receiving position for the fingers 30 of the arms 31. The arms 31 being thus released, the springs 35 draw the said arms and their 25 fingers 30 inwardly thus projecting the said fingers 30 forcibly through the perforations 29 and against the springs 26 of the locking plates 24 as best illustrated in Figs. 5 and 8 of the drawings whereby the plates 24 are 30 forced toward each other into locking engagement with the hand of the operator. During this operation, the head 40 of the arm 39 draws the switch 42 outwardly to cause the contact points 15 and 16 to engage 35 and complete the circuit to sound the alarm. The alarm having been thus turned in and the wrist of the operator being retained by the locking plates 24, the fire department 40 will respond to the alarm and upon reaching 45 the box may be advised as to the existence or location of a fire.

A resetting mechanism for the arms 31 is provided consisting of a lever pivoted as at 48 to a bracket 49 within the box 10 and 50 lying substantially parallel to the aforementioned bracket 12. The said lever has a recessed end 50 adapted to engage over the lever 36 and force the lever end 39 inwardly so as to be readily reengaged by 55 the slotted end 42 of the switch arm 13, and thus releasing the arm engaging members 19 which may be readily swung to their open positions with the members again positioned as shown in Fig. 3, a lever 51 and 60 connecting link 52 being employed for the 65

said resetting lever 47. It is to be understood that a lock may be provided for the lever 51 if desired such as a hasp 53 and padlock 54, although the location and operation of the said lever will not be at once 70 apparent to the operator of the alarm so that he will not be advised as to the manner of releasing the retaining means for the locking plates 24.

While the form of the invention herein 75 shown and described is what is believed to be the preferred embodiment thereof, it is nevertheless to be understood that minor changes may be made therein without departing from the spirit and scope of the 80 invention as claimed.

What I claim as new is:—

1. In combination with a fire alarm box having a front opening and provided with an electric switch therein, coöperating arm-engaging members right-angular in cross-section oppositely pivoted interiorly of the said box intermediate the said opening and switch, slidable wrist-engaging plates carried by the said arm engaging members, 85 normal retracting means for the said plates, and automatic projecting means for the said plates operable simultaneously with the switch closing operation.

2. In combination with a fire alarm box 90 having a front opening and provided with an electric switch therein, coöperating arm-engaging members right-angular in cross-section oppositely pivoted interiorly of the said box intermediate the said opening and switch, slidable wrist-engaging plates carried by the said arm-engaging members, normal retracting means for the said plates, spring-pressed arms pivoted within the said box and having angular fingers in resilient 95 engagement with the said arm engaging members, and coöperative circuit closing means carried by the switch and arms.

3. A device of the class described comprising a box having a forward opening 100 therein, and an electric switch for a fire alarm circuit positioned inwardly of the said opening, arm engaging members oppositely pivoted within the said box and having angularly disposed plates, one of said plates being adapted for overlapping relations 105 when the said switch is open, the other of said plates having coöperating arm-engaging cut-away portions.

4. A device of the class described comprising a box having a forward opening 110 therein, and an electric switch for a fire alarm circuit positioned inwardly of the said opening, arm engaging members oppositely pivoted within the said box and having angularly disposed plates, one of said plates being adapted for overlapping relation 115 when the said switch is open, the other of said plates having coöperating arm-engaging cut-away portions, wrist locking 120 125 link 130

plates slidably positioned within the said cut-away plates, normal retracting springs for the said locking plates, and automatic projecting means for the said locking plates 5 operable when the said plates are positioned in the same plane.

5. A device of the class described comprising a box having a forward opening therein, and an electric switch for a fire alarm circuit 10 positioned inwardly of the said opening, arm-engaging members oppositely pivoted within the said box and having angularly disposed plates, one of said plates being adapted for overlapping relation when the 15 said switch is open, the other of said plates having coöperating arm-engaging cut-away portions, wrist locking plates slidably positioned within the said cut-away plates, normal retracting springs for the said locking 20 plates, resiliently mounted arms pivoted within the said box and having inturned fingers positionable within the plane of the said locking plates when the locking plates are swung to a position in the same plane.

6. A device of the class described comprising a box having a forward opening therein, and an electric switch for a fire alarm circuit positioned inwardly of the said opening, arm-engaging members oppositely pivoted within the said box and having angularly disposed plates, one of said plates being adapted for overlapping relation when the said switch is open, the other of said plates having coöperating arm-engaging cut-away portions, wrist locking plates slidably positioned within the said cut-away plates, normal retracting springs for the said locking plates, resiliently mounted arms pivoted within the said box and having inturned flanges positioned within the 40 plane of said locking plates when the locking plates are swung to a position in the same plane, sliding connections between the rear ends of the said arms, and coöperative circuit closing means carried by the switch 45 and arms.

In testimony whereof I affix my signature,
EDMUND TOKARSKI.
